CLAIM

The ornamental design for a fashion ornament as shown and described.

DESCRIPTION

FIG. 1 is a front perspective view of a fashion ornament in the environment of a shoe showing my new design; FIG. 2 is a back perspective view thereof; FIG. 3 is a right side view thereof; FIG. 4 is a left side view thereof; FIG. 5 is a front view thereof; and, FIG. 6 is a top view thereof. The broken lines in the figures depicting the shoe environment form no part of the claimed design.

1 Claim, 6 Drawing Sheets
